(57) **CLAIM**

The ornamental design for laptop case including a top and a bottom, as shown and described.

DESCRIPTION

FIG. 1 is a front elevational view of the top of the laptop case including a top and a bottom showing my new design; FIG. 2 is a rear elevational view of the top of the laptop case including a top and a bottom;

FIG. 3 is a left side elevational view of the top of the laptop case including a top and a bottom;

FIG. 4 is a right side elevational view of the top of the laptop case including a top and a bottom;

FIG. 5 is a top plan view of the top of the laptop case including a top and a bottom;

FIG. 6 is a bottom plan view of the top of the laptop case including a top and a bottom;

FIG. 7 is a front perspective view of the top of the laptop case including a top and a bottom;

FIG. 8 is a front elevational view of the bottom of the laptop case including a top and a bottom;

FIG. 9 is a rear elevational view of the bottom of the laptop case including a top and a bottom;

FIG. 10 is a left side elevational of the bottom of the laptop case including a top and a bottom;

FIG. 11 is a right side elevational view of the bottom of the laptop case including a top and a bottom;

FIG. 12 is a top plan view of the bottom of the laptop case including a top and a bottom;

FIG. 13 is a bottom plan view of the bottom of the laptop case including a top and a bottom;

FIG. 14 is a front perspective view of the bottom of the laptop case including a top and a bottom; and,

FIG. 15 is a perspective view of the laptop case including a top and a bottom.

The broken lines depict portions of the laptop case including a top and a bottom that form no part of the claim.

1 Claim, 15 Drawing Sheets
